UNITED STATES PATENT OFFICE.

GEORGE S. MYERS, OF ELECTRA, TEXAS.

DRILL-COLLAR.

1,132,375.

Specification of Letters Patent. Patented Mar. 16, 1915.

Application filed April 8, 1914. Serial No. 830,474.

To all whom it may concern:

Be it known that I, GEORGE S. MYERS, a citizen of the United States, residing at Electra, in the county of Wichita and State 5 of Texas, have invented new and useful Improvements in Drill-Collars, of which the following is a specification.

This invention relates to drill collars and in particular to collars used upon rotary drills of the type which are water-flushed.

10 In drills of this type, it is the usual practice to employ a collar which is threaded onto the lower end of the operating drill pipe and is adapted for threaded connection with the bit. The threaded connection between the bit and collar, though substantially watertight, is objectionable for the reason that the threads are apt to become worn and distorted by the incessant shock incident with 15 the impact of the bit against the rock through which it is cutting, whereby the bit is apt to become detached while operating in the bore. A detached bit, as should be readily understood by persons familiar with the 20 art to which this invention relates, is always a source of great inconvenience, and, when it can not be recovered, it necessitates the abandonment of the bore, which means that a new bore must be drilled, possibly 25 after days and weeks of fruitless effort expended upon the original bore. It is, therefore, my purpose to provide a drill collar having means embodied therein for securing the drill bit positively thereto and in a 30 manner which precludes the possibility of accidental detachment while in use.

A further object of the invention is to provide a collar of this character wherein the means for securing a drill bit thereto is 35 in the form of a wedge-shaped key which extends transversely through slots provided in the same.

A still further object is to provide a securing key of this construction which is adjustable within the slots so as to permit effective binding of the bit in position, but which is provided with means for preventing loss of the flushing liquid through the collar slots, though the flow of the same onto 45 the bit is uninterrupted.

The invention consists in the features of construction, combination, and arrangement of parts, hereinafter fully described and claimed, reference being had to the accompanying drawings, in which:

Figure 1 is a side elevation of the collar

mounting a bit upon a drill pipe, the latter being broken away; Fig. 2 is a longitudinal sectional view on line 2—2 of Fig. 1; and, Fig. 3 is a transverse sectional view on line 3—3 of Fig. 2.

In the drawing, the numeral 1 designates a portion of the ordinary form of drill pipe, whose lower end is externally screw-threaded at 2 for engagement within the threaded 65 socket 3 provided in the upper end of my improved collar 4. This collar is provided in its lower end and in communication with the socket 3 with a longitudinally tapered socket 5, which is substantially rectangular 70 in transverse section, for the snug reception of the shank 6 of the drill bit 7. The bit socket 5 of the collar is provided in its opposite side walls with longitudinally extending grooves 8 which lead downwardly 75 from the socket 3 and form liquid ducts which are adapted to register with the conducting grooves 9 formed in the corresponding sides of the bit. The collar is provided further with a transverse key slot 10 in communication with the socket 5. This slot is 80 adapted to receive a diametrically adjustable securing key 11, the lower face 14 of the latter being disposed at right angles to the axis of the drill collar irrespective of 85 adjustment. This key is adapted to extend through the slot 15 provided in the shank 6 of the drill bit with its inclined upper face 12 in active engagement with the inclined upper wall 13 of the said slot. The 90 small and large ends of the key 11 are screw-threaded as at 17 and 18 respectively. Adjusting nuts 19 and 20 are engaged with the said threaded ends 17 and 18 of the key and are adapted to be countersunk within 95 enlarged recesses 21 and 22, which are provided in the sides of the collar in communication with the key slot. These recesses are constructed larger in diameter than the key slot so that the marginal edges of the adjusting nuts will extend past the edges of the slot so as to seal the slot and thus prevent leakage of the flushing liquid there-through.

From the foregoing description, taken in 105 connection with the accompanying drawings, it should be apparent that the securing key will fasten the bit shank securely within the collar socket, so as to obviate danger of accidental detachment thereof, and that the 110 nuts by which the key is adjusted, either in attaching or detaching the same, will serve

to seal the key slot to prevent leakage, but will not protrude outwardly from the collar to present obstructions to the proper operation of the drill.

5. What is claimed is:

1. The combination with a drill pipe of the class described, of a drill collar adapted to be secured to the lower end of the said pipe, the said collar being provided with a longitudinally tapering socket in communication with the bore of the pipe, a drill bit having a tapered shank adapted for engagement within the hollow socket, the said shank and collar being provided with transverse key slots communicating with the socket, and a securing key adapted to be mounted within the said key slots.

2. The combination with a drill pipe of the class described, of a drill collar adapted to be secured to the lower end of the said pipe, the said collar being provided with a longitudinally tapering socket in communication with the bore of the pipe, a drill bit having a tapered shank adapted for engagement within the hollow socket, the said shank and collar being provided with transverse key slots communicating with the socket, and a wedge-shaped securing key adapted to be mounted adjustably within the said key slots.

3. The combination with a drill pipe of the class described, of a drill collar adapted to be secured to the lower end of the said pipe, the said collar being provided with a longitudinally tapering socket in communication with the bore of the pipe, a drill bit having a tapered shank adapted for engagement within the hollow socket, the said shank and collar being provided with transverse key slots communicating with the socket, a wedge-shaped securing key adapted to be mounted adjustably within the said key slots, and means by which the key may be adjusted.

4. The combination with a drill pipe of the class described, of a drill collar adapted to be secured to the lower end of the said pipe, the said collar being provided with a longitudinally tapering socket in communication with the bore of the pipe, a drill bit having a tapered shank adapted for engagement within the hollow socket, the said shank and collar being provided with transverse key slots communicating with the socket, and a wedge-shaped securing key

adapted to be mounted adjustably within the said key slot, the upper wall of the key slot in the shank and the adjacent edge of the key being longitudinally inclined, the opposite edge of the key and the lower wall 60 of the key slot in the bit shank being straight.

5. The combination with a drill pipe of the class described, of a drill collar adapted to be secured to the lower end of the said pipe, the said collar being provided with a longitudinally tapering socket in communication with the bore of the pipe, a drill bit having a tapered shank adapted for engagement within the hollow socket, the said 70 shank and collar being provided with transverse key slots communicating with the socket, a wedge-shaped securing key adapted to be mounted adjustably within the said key slots, the smaller end of the said key 75 being screw-threaded, the collar being provided in its outer face in communication with the key slot therein with an enlarged recess, and an adjusting nut engaged with the threaded end of the key and seated in the recess in the collar.

6. The combination with a drill pipe of the class described, of a drill collar adapted to be secured to the lower end of the said pipe, the said collar being provided with a 85 longitudinally tapering socket in communication with the bore of the pipe, a drill bit having a tapered shank adapted for engagement within the hollow socket, the said shank and collar being provided with trans- 90 verse key slots communicating with the socket, a wedge-shaped securing key adapted to be mounted adjustably within the said key slots, the collar socket and the bit being provided with registering liquid-conducting 95 grooves communicating with the bore of the drill pipe, the collar being provided at the opposite ends of the key slot with enlarged recesses, the opposite ends of the key being screw-threaded, and an adjusting nut adapted 100 to be engaged with each end of the key and mounted within the corresponding collar recess in engagement with its inner wall and projecting marginally from the key slot.

In testimony whereof I affix my signature 105
in presence of two witnesses.

GEO. S. MYERS.
